US00D978810S

(12) **United States Design Patent** (10) Patent No.: **US D978,810 S**
Lee et al. (45) Date of Patent: **** Feb. 21, 2023**

(54) **LED MATRIX DISPLAY**(71) Applicant: **AGS LLC**, Las Vegas, NV (US)(72) Inventors: **Sigmund Hyunjai Lee**, Atlanta, GA (US); **Rachel Calhoun Lewis**, Atlanta, GA (US); **Daniel Kendall Harden**, Palo Alto, CA (US); **Benjamin Martin**, South San Francisco, CA (US)(73) Assignee: **AGS LLC**, Las Vegas, NV (US)(**) Term: **15 Years**(21) Appl. No.: **29/700,251**(22) Filed: **Jul. 31, 2019**(51) LOC (14) Cl. **14-03**

(52) U.S. Cl.

USPC ..... **D14/125**; D21/369(58) **Field of Classification Search**

USPC ..... D14/204, 209.1, 211, 221, 224–225, D14/227–228, 239, 371, 372, 373, D14/447–452, 125–129, 335–337, D14/374–377, 341, 440–442, 444, D14/446–447, 250, 217, 344–345, D14/348–349, 351–359, 363, 900; D8/355, 363, 373, 349; D6/672, 682, D6/300–314; D13/107, 101–103, D13/118–119, 184, 199; D10/30, 103, D10/123, 125, 132; D16/101, 216–217; D12/106; D24/103, 138, 140–144 CPC G06F 3/1446; G06F 1/20; G06F 1/1628; G06F 1/1626; G06F 1/1669; G06F 1/1679; A47F 5/0807; G09G 2356/00; G09G 2370/04; F16M 11/2085; F16M 11/2092; F16M 11/2007; F16M 11/2014; F16M 11/2021; F16M 11/105; F16M 11/10; F16M 11/048; F16M 11/12; F16M 13/022; H04R 9/06; H04R 1/24; H04R 11/02; H04R 2400/00; H05K 5/00; H05K 5/0213; H05K 5/30; H05K 5/03; H05K 5/0017; A47B 23/044; A47B 97/001; A47B 81/061; H04B 1/3888; A45C

CLAIM

The ornamental design for an LED matrix display, as shown and described.

DESCRIPTION

FIG. 1 is a front perspective view of an LED matrix display of the present disclosure.

FIG. 2 is a front elevation view thereof.

FIG. 3 is a rear elevation view thereof.

FIG. 4 is a first side view thereof.

FIG. 5 is a second side view thereof.

FIG. 6 is a top plan view thereof.

FIG. 7 is a front elevation view thereof illustrating the LED matrix display in a gaming environment.

FIG. 8 is a front perspective view of an LED matrix display according to a second embodiment of the present disclosure.

FIG. 9 is a front elevation view thereof.

FIG. 10 is a rear elevation view thereof.

FIG. 11 is a first side view thereof.

FIG. 12 is a second side view thereof.

FIG. 13 is a top plan view thereof.

FIG. 14 is a front elevation view thereof illustrating the LED matrix display in a gaming environment.

FIG. 15 is a front perspective view of an LED matrix display according to a third embodiment of the present disclosure.

FIG. 16 is a front elevation view thereof.

FIG. 17 is a rear elevation view thereof.

FIG. 18 is a first side view thereof.

FIG. 19 is a second side view thereof.

FIG. 20 is a top plan view thereof.

FIG. 21 is a front elevation view thereof illustrating the LED matrix display in a gaming environment.

FIG. 22 is a front perspective view of an LED matrix display according to a fourth embodiment of the present disclosure.

FIG. 23 is a front elevation view thereof.

FIG. 24 is a rear elevation view thereof.

FIG. 25 is a first side view thereof.

FIG. 26 is a second side view thereof.

FIG. 27 is a top plan view thereof.

FIG. 28 is a front elevation view thereof illustrating the LED matrix display in a gaming environment.

FIG. 29 is a front perspective view of an LED matrix display according to a fifth embodiment of the present disclosure.

FIG. 30 is a front elevation view thereof.

FIG. 31 is a rear elevation view thereof.

FIG. 32 is a first side view thereof.

FIG. 33 is a second side view thereof.

FIG. 34 is a top plan view thereof.

FIG. 35 is a front elevation view thereof illustrating the LED matrix display in a gaming environment.

FIG. 36 is a front perspective view of an LED matrix display according to a sixth embodiment of the present disclosure.

FIG. 37 is a front elevation view thereof.

FIG. 38 is a rear elevation view thereof.

FIG. 39 is a first side view thereof.

FIG. 40 is a second side view thereof.

FIG. 41 is a top plan view thereof.

FIG. 42 is a front elevation view thereof illustrating the LED matrix display in a gaming environment.

FIG. 43 is a front perspective view of an LED matrix display according to a seventh embodiment of the present disclosure.

FIG. 44 is a front elevation view thereof.

FIG. 45 is a rear elevation view thereof.

FIG. 46 is a first side view thereof.

FIG. 47 is a second side view thereof.

FIG. 48 is a top plan view thereof; and,

FIG. 49 is a front elevation view thereof illustrating the LED matrix display in a gaming environment.

The shade lines in the Figures show contour and not surface ornamentation. The broken lines in the Figures show portions of the support structure and its surrounding environment that form no part of the claimed design.
